UNITED STATES PATENT OFFICE.

PHILIP GORDON BROWN, OF DULUTH, MINNESOTA.

ROBE-RAIL.

1,129,379.

Specification of Letters Patent. Patented Feb. 23, 1915.

Application filed December 11, 1914. Serial No. 876,726.

To all whom it may concern:

Be it known that I, PHILIP GORDON BROWN, a citizen of the United States, residing at Duluth, in the county of St. Louis 5 and State of Minnesota, have invented a new and useful Robe-Rail, of which the following is a specification.

The present invention appertains to robe rails or racks for motor vehicles, and aims 10 to provide an automobile accessory of that character, provided with novel means for holding or clamping a robe, garment, or other object, which is placed over the rail or rack, whereby the robe or other article may 15 be held in a secure manner to prevent the theft thereof.

Another object of this invention, is to provide a device of the character indicated, embodying an end bracket or fixture for the 20 rod or rail proper, and provided with key-controlled means for clamping or gripping the robe, garment or other article thrown over or placed upon the rod or rail.

Another object of the invention, is the 25 provision of a robe rail or rack, resembling in general outline, an ordinary robe rail or rack, and including end brackets or fixtures which are attachable to the body of the automobile, one or both of the end brackets 30 embodying novel means for securing the robe, garment, or the like.

It is also within the scope of the invention 35 to provide a robe rail or rack of the nature indicated, which is comparatively simple, inexpensive, compact and non-encumbering in construction, which is fool-proof, which may be readily applied to an automobile body in the manner of an ordinary robe rail or rack, and which will be convenient, efficient and thoroughly practical in use.

With the foregoing and other objects in view which will appear as the description 45 proceeds, the invention resides in the combination and arrangement of parts and in the details of construction hereinafter described and claimed, it being understood that changes in the precise embodiment of the invention herein disclosed, can be made 50 within the scope of what is claimed, without departing from the spirit of the invention.

The invention is illustrated in its preferred embodiment in the accompanying drawing, wherein:—

Figure 1 is a plan view of the improved 55 robe rail or rack, parts being broken away,

and parts being shown in section. Figs. 2 and 3 are sectional views taken on the lines 2—2 and 3—3, respectively, of Fig. 1. Fig. 4 is an elevation of the key for operating the locks.

In carrying out the invention, the robe rail or rack comprises a pair of end or corner brackets or fixtures 1, which are connected by a rail member or rod 2, and which are adapted to be attached to the automobile 60 body through the medium of attaching devices 3. The brackets 1 are each in the form of an elbow, or L-shaped, and are also preferably in the form of castings. Each of the brackets 1, as illustrated, embodies a key-controlled lock and clamp for gripping the robe, although it is to be understood, at the outset, that the brackets 1 are duplicated in the present showing, and if desired, only one of the brackets need embody the lock and 65 clamp, while the other bracket is used solely for supporting or carrying the adjacent end of the rod 2. It is therefore evident that one or two of the brackets embodying the lock and clamp may be employed in the rail or 70 rack, according to the whim of the user or purchaser.

The bracket 1, which is in the form of an elbow, has one arm, designated 4, provided with a longitudinally open ended bore or 75 socket 5, receiving one end of the rod or rail proper 2 to support and carry the same. Thus, the ends of the rod 2 being engaged into the arms 4 of the brackets 1, enable the 80 rod 2 to be properly carried by the brackets, so that the rod and brackets provide the rack or rail for receiving and holding the robe, or other article. The other arm of the bracket 1 is tubular, and is adapted to be attached through the medium of the device 85 3, to the body of the automobile, or to any other suitable support. The device 3 embodies a cap 7 threaded or otherwise secured over the end of the arm 6, and provided with an ear 8 projecting therefrom and pivoted 90 between a pair of outstanding ears 9 carried by a base plate 10 which is adapted to be secured by screws or other securing means to the automobile body or other support. The ear 8 is preferably pivoted between the ears 9, by means of a pivot screw or element 11 engaged through the ears. Thus, when the plates 10 are attached to the automobile body or other support, the rack may be swung 95 perpendicularly or angularly relative to the 100 110

body for conveniently receiving a robe, and may also be swung against or adjacent the body so as to be out of the way.

The bore 12 of the arm 6 is provided with a counterbore or enlarged recess 13 at the end of the arm 6, and is provided with an inwardly projecting annular flange or contracted portion 11 at the crotch portion or elbow of the bracket 1, and defining a key-receiving socket or recess 15 at that end of the bore 12 remote from the recess 13 and adjacent the bend or elbow of the bracket. That side of the arm 6 adjacent the arm 4 is provided with a longitudinal slot 16 communicating with the bore 12. The arm 4 of the bracket 1, which receives and holds the corresponding end of the rod 2, is also in the form of a jaw, to constitute a portion of the clamp. The jaw 4 is a fixed or stationary one, relative to the rack, and a movable jaw 17 is disposed adjacent the inner side of the arm 4 to cooperate therewith, and is provided with a web-like shank 18 passing slidably through the slot 16, and having a circular nut 19 slidable within the bore 12 of the arm 6, to guide the movable jaw 17 for proper movement to and from the arm or jaw 4.

The key-controlled device or lock embodies a screw 20, disposed within the bore 12, preferably having a square thread, and upon which the nut 19 is threaded, the inner end of the screw 20 having a stem 21 projecting therefrom and journaled through a washer 22 seated within the recess 13, a collar or retaining element 23 being secured upon the stem 21 to bear against the washer 22, for holding the screw against outward movement or removal while the device is assembled. The collar 23 is preferably secured in place by means of a cotter pin 24 engaged therethrough and through the stem 21, although other securing means may be utilized. It is to be noted in this connection that the cap 7 of the attaching means or device 3, covers the inner end of the bore 12, and houses the parts 21, 22 and 23, to prevent tampering therewith. It is also to be noted that when the plates 10 are attached to the automobile body or support, the brackets 1 and caps 7 cannot be unscrewed, for separating them.

The outer end of the screw 20 is provided with a smooth reduced portion 25 journaled through the collar or contracted portion 11 of the bore 12, and a key-engaging projection 26 projects from the portion 25 within the key socket or cavity 15, and terminates therein, to prevent the unwarranted or malicious operation of the lock and clamp without the employment of a proper key. A key 27, such as shown in Fig. 4, is employed for rotating the screw 20 of the lock, which controls the movement of the jaw 17 of the clamp, the shank of the key being provided

with a suitable bit insertible into the key socket 15 for engagement with the projection 26 of the screw 20, whereby when the key is rotated, the screw 20 will be rotated accordingly for moving the jaw 17. The interfering portions of the key 27 and key engaging projection or portion 26 of the screw, may be altered in various manners, to provide suitable key changes, so that it will necessitate a special form of key 27 for each lock, and to thereby prevent a person possessing a key for one lock, from operating the lock of another robe rail.

The jaws 4 and 17 are preferably faced with rubber or other compressible or yielding material, as at 28, whereby the jaws may more effectively grip the robe, and prevent the withdrawing or releasing of the same, until the jaws are opened.

In use, to lock or secure the robe upon the rail or rod 2, while the vehicle is unoccupied, and to prevent the theft of the robe or other article, the robe is inserted between the arm or jaw 4 and jaw 17, and the key 27 is then introduced into the socket 15 of the respective bracket 1, which will enable the screw 20 to be rotated for moving the jaw 17 toward the arm or jaw 4 for clamping or gripping the robe. When the robe is gripped tightly, the key is withdrawn, and it is then most inconvenient, if not impossible, for an unwarranted or maliciously inclined person to release the robe, for purpose of stealing the same. The cap 7 constitutes a housing to protect the connection between the feed-screw and the inner end of the stationary jaw member, and at the same time forms the means of connection between the said member and the pivotal ear 8 which is mounted on the base plate 10.

The working parts of the lock are concealed or housed so as to prevent tampering therewith, and it will be noted that the parts of the present device are so assembled as to enable the device to be utilized in a convenient and ready manner and without interference, for receiving and holding the robe, garment, or other article, one or both end brackets or members of the rail or rack being provided with means for clamping or securing the robe. The other advantages and capabilities of the present invention are thought to be obvious to those versed in the art, without further description being necessary.

Having thus described the invention, what is claimed is:-

1. A vehicle robe rail bracket having relatively movable members, provided with substantially coextensive robe-engaging jaws, and the outer of which is adapted to support the end of a robe rail, one of said jaws being parallel with the rail and the other jaw in alignment with the rail and one of said members being provided with means for attachment to a vehicle body, and key-actuated

- means for forcibly adjusting and locking the movable member with said jaws in robe-engaging relation.
2. A robe rail bracket having an L-shaped member, one arm of which is adapted for attachment to a vehicle body and the other arm of which constitutes a stationary clamp jaw and is constructed to engage and support one end of a robe rail, a movable clamp-jaw mounted to coöperate with the inner side of and coextensive with the stationary clamp jaw, and means for forcibly adjusting and holding the movable jaw in clamp-ing relation with the stationary jaw.
3. A robe rail comprising an angular end bracket, a rod having one end engaged to one arm of the bracket, the said arm of the bracket forming a jaw, the other arm of the bracket having a bore extending there-

through, means for attaching the bracket to 20 a support including a cap engaged over and housing the end of the second mentioned arm of the bracket, a screw mounted within the said bore and swivelly secured to the bracket within said cap and having key en-gaging means within the bore at that end 25 remote from the said cap, and a movable jaw coöperating with the aforesaid jaw and having a nut movable within the said bore and threaded upon the screw.

In testimony that I claim the foregoing as my own, I have hereto affixed my signature in the presence of two witnesses.

PHILIP GORDON BROWN.
